UNITED STATES PATENT OFFICE

2,120,868

AUTOMATIC POLISH FEEDER

Harry S. Reed, Yakima, Wash.

Application May 11, 1936, Serial No. 79,117

1 Claim. (Cl. 51—263)

This invention relates to automatic polish feeders and has for the primary object the provision of a device which is especially adapted for efficiently distributing abrasive to a lens polishing tool or machine or for any other purpose wherein it is desired to have abrasive spread on a surface.

With these and other objects in view this invention consists in certain novel features of construction, combination and arrangement of parts to be hereinafter more fully described and claimed.

For a complete understanding of my invention, reference is to be had to the following description and accompanying drawings, in which

Figure 1 is a side elevation partly in section illustrating an automatic polish feeder constructed in accordance with my invention.

Figure 2 is a top plan view illustrating the same.

Figure 3 is a diagrammatical view illustrating a series of feeders operating from a single compressor; and

Figure 4 is a detail sectional view illustrating the adjustable mounting for the brush.

Referring in detail to the drawings, the numeral 1 indicates a suitable base on which is mounted a vertically arranged standard 2 carrying a tank or reservoir 3 for containing abrasive and is provided with an outlet valve 4 to which is connected a flexible tube 5.

A distributing brush 6 consisting of a brush head 7 carrying bristles 8 and a handle 9 is molded to the head. The handle 9 is engaged by an adjustable clamp 10 having a swivel connection 11 to the base 1 whereby the brush may be moved or arranged in several adjusted positions so as to contact with a surface. Mounted in the head 7 of the brush is a tube 12 one end 40 of which terminates within the bristles 8 while the other end extends outwardly of the head and is connected to a flexible tube 13. A Y-shaped coupling 14 is connected to the tube 13 and to

the tube 5 and to a tube 15, and the latter is in turn connected to the outlet 16 of a compressor 17 mounted on the base 1. A drive shaft 18 is geared to the compressor, as shown at 19, and is connected to an electric motor 20 mounted on the base and equipped with a rheostat 21 for the purpose of regulating speed of rotation of the motor. A fly wheel 22 is secured to the drive shaft 18.

After the brush 6 has been adjusted to a surface, the valve 4 is opened to permit the abrasive of the tank 3 to pass into the Y 14. The compressor 17 driven by the motor 20 forces air into the coupling 14 which mingles with the abrasive and forces the latter between the bristles of the brush onto the surface. The compressor 17 is of the type having a reciprocating piston (not shown) so that the air expelled therefrom will be intermittent to the coupling 14 thereby ejecting the abrasive through the brush onto the surface with intermittent impulses.

A device constructed in accordance with the foregoing will efficiently distribute the abrasive onto a surface, such as a grinding or polishing element of a lens polishing machine or tool and obviates the customary practice of manually placing the abrasive on a surface by a brush operated manually. If desired, a series of abrasive distributors constructed in accordance with the foregoing may be operated from a single compressor, as shown in Figure 3.

What is claimed is:

An automatic polish feeder comprising a base, a fountain type brush adjustably mounted on the base, an abrasive supply tank carried by the base, an outlet valve for said tank, a power driven compressor mounted on said base, flexible tubes connected to said valve, compressor and the brush, and a Y-shaped coupling connecting the tubes whereby the contents of the tank may commingle with air from the compressor and be forced by the air through the brush.

HARRY S. REED.
